UNITED STATES PATENT OFFICE.

LOUIS G. STRNAD, OF CHICAGO, ILLINOIS.

DESIGN FOR A TOOTHBRUSH AND PASTE HOLDER.

Application filed May 21, 1924. Serial No. 9,672. Term of patent 14 years.

To all whom it may concern:

Be it known that I, LOUIS G. STRNAD, a citizen of Czechoslovakia, residing at Chicago, in the county of Cook and State of Illinois, have invented a new, original, and ornamental Design for a Toothbrush and Paste Holder, of which the following is a specification, reference being had to the accompanying drawing, forming part thereof.

The figure is a view in perspective of a tooth brush and paste holder, showing my new design.

I claim:

The ornamental design for a toothbrush and paste holder, as shown.

LOUIS G. STRNAD.
